Inventor
G. H. Kidney

UNITED STATES PATENT OFFICE.

GEORGE H. KIDNEY, OF CLEVELAND, OHIO.

IMPROVED WASHING-MACHINE.

Specification forming part of Letters Patent No. 36,568, dated September 30, 1862.

To all whom it may concern:

Be it known that I, GEORGE H. KIDNEY, of Cleveland, in the county of Cuyahoga and State of Ohio, have invented a new and Improved Washing-Machine for Washing Textile Fabrics, &c.; and I do hereby declare that the following is a full and exact description thereof, reference being had to the accompanying drawings, and to the letters of reference marked thereon—like letters referring to like parts—in which—

Figure 1 is a transverse end view, Fig. 2 a transverse side view, Fig. 3 a top view, Fig. 4 a perspective view, of the mode by which the fabric is secured to the cylinder; and Fig. 5 is a perspective view of the machine.

The nature of my invention consists in the construction of a washing-machine provided with a cylinder, the exterior of which cylinder is covered with balls for the purpose of forming a rough surface, and under which cylinder is secured a bed-plate, which also is formed by passing balls onto cords, forming a rough-surfaced self-adjusting bed-plate, and between which cylinder and bed-plate the fabric to be washed is passed by the action of the cylinder, thus applying friction to the fabric for the purpose of washing and cleaning the same.

To enable others skilled in the art to make and use my invention, I will proceed to describe its construction and operation.

M, Fig. 1, is a box provided with four legs. A is a cylinder.

G is a shaft, to which a shank and handle are attached. Shaft G passes through and is secured to cylinder A, resting on the edge of box M. The balls d d d d are strung on cords B B B B, and are secured to the cylinder by said cords being passed through holes in the bars J J.

I is a bar used for the purpose of securing the article to be washed to the cylinder. One end of this bar is provided with a bolt, which bolt passes through one end of the cylinder A, and the other end of the bar I is secured by means of hook K, as represented in Figs. 4 and 5. The balls C C C C form the bed-plate. These balls are strung on cords e e e e e, one end of which cords is held by the cross-bar H and the other ends are passed over the

pulleys L L L L on the cross-bar O, and are held in a correct position by means of weights P, Fig. 2. The slots N N in box M show the means by which the cross-bars H and O are secured, and which slots also permit the adjustment of the bed-plate to correspond with the thickness of the article to be washed. f is a faucet, by the use of which the water is drawn from the box.

When a washing is to be done, water is put into the box and the articles to be washed are secured to the cylinder by means of the cross-bar I. The cylinder is then turned around, or it may be worked back and forth. The balls, being stationary on the cords, cause friction to be created on the fibers of the article thus rubbed, and the bed-plate, being formed by strings of balls, each of which string of balls acts independently of the other, held by separate weights, yields exactly to correspond with the uneven thicknesses of the articles pressed between the cylinder and the bed-plate without producing the injury to the goods in washing that is usual by the use of the common hand wash-board, and with more ease and a saving of labor to the person employed to do such work.

The machine may be made of any desirable size that use and experience may dictate to make a cheap and efficient machine.

I do not claim to be the first and original inventor of a washing-machine, as many valueless inventions for such purposes have heretofore been put in use; but

What I claim as my improvement, and desire to secure by Letters Patent of the United States, is—

1. The rough-surfaced self-adjusting bed-plate, when the same is constructed substantially as described, and for the purpose set forth.

2. The combination of the rough-surfaced self-adjusting bed-plate and the rough-surfaced cylinder, when the several parts are constructed and arranged substantially as described, and for the purpose set forth.

G. H. KIDNEY.
